WORK-TRANSFER MEANS FOR EYELET MACHINES AND THE LIKE

Arthur L. Williams, Waterbury, Conn., assignor to The American Brass Company, a corporation of Connecticut

Application July 26, 1941, Serial No. 404,173

11 Claims. (Cl. 113—40)

This invention relates to work-transfer means for eyelet machines and the like, and has for its principal object to provide improved work-transfer means capable of adjustment to accommodate work-pieces of different sizes and shapes. The work-transfer means of the invention is especially suited for use as the blank-transfer means for transferring a stamped-out blank from the blanking stage to the first forming stage of an eyelet machine or the like.

Eyelet machines generally are provided with a blanking punch which, in cooperation with a blanking die, stamps out blanks of suitable size and shape to be formed by drawing and stamping operations into finished articles. In a fully automatic eyelet machine or the like, it is necessary to provide means for transferring the blanks from the blanking stage to the first forming stage, and for transferring the partially formed pieces from each forming stage to the next. For this purpose it is usual to provide a slide carrying a blank-transfer block and a series of work-transfer fingers. The slide reciprocates in timed relation with the blanking and forming punches so that the blank-transfer block and the work-transfer fingers may operate to move a fresh work-piece into position to be acted upon at each stroke of the several forming punches.

The blank-transfer block ordinarily employed heretofore for transferring the blank from the blanking stage to the first forming stage is a generally ring-shaped block with a central opening of just the right size to receive the blank delivered to it by the blanking punch and to hold it firmly. It is necessary that the blank be held firmly once it has been pressed into the transfer block by the blanking punch, so that it will not be partially or wholly withdrawn on the upstroke of the punch. Unless the transfer block grips the blank firmly, such accidental withdrawal could easily occur because of the tendency for the lubricant with which the punch and the blank are coated to cause the latter to adhere slightly to the punch face. In addition, the transfer block must hold the blank firmly so that it will be properly centered upon delivery to the forming stage. If the blank is askew in the transfer block, it will not be properly shaped by the forming punch and die, and may even catch in the forming stage in a manner that will cause the punch to be damaged or broken. Consequently, it has been the common practice to form the central opening of the work-transfer block with a slight draft, making the opening slightly larger at the top of the block (where the blank enters) than

at the bottom (where it is to be held). This construction enables the work-piece to enter the block easily and causes it to be held tightly once it has been pressed to the bottom of the block.

Blank transfer blocks of the character described are not entirely satisfactory. The surface of the block where it engages the blank wears quite rapidly on account of repeated insertions of new blanks. When it has worn to even a very slight degree, it is no longer capable of firmly holding the blank, and either a new blank-transfer block must be made, or the old block must be removed and its bottom surface must be peened to restore the work-receiving opening to its original size.

Either operation is expensive, and although peening is less expensive than making a new block, it is only possible to peen the block a few times before it is damaged beyond repair.

A further disadvantage of the heretofore commonly used transfer block is that it will accommodate only one particular size of blank. If the blank size is changed by even a very small fraction of an inch, a new blank transfer block must be provided.

The present invention provides improved work-transfer means for eyelet machines or like which may be adjusted to accommodate blanks or other work-pieces of different sizes, and which can be adjusted readily to compensate for the effects of wear.

In accordance with the present invention the slide of an eyelet machine or the like carries work-transfer means comprising a plurality of work-engaging fingers. The fingers are adjustable in the plane of the slide to accommodate work-pieces of different sizes, and means such as clamps are provided for securing the fingers rigidly in a chosen position with respect to the slide. The work-engaging fingers should be made rigid so that a work-piece held thereby will be accurately aligned when transferred into position to be acted upon by the next successive punch and die (or other forming tools). The clamps or other means for securing the fingers into position are arranged to be loosened to permit adjustment of the fingers and to be tightened to hold the fingers rigidly in the chosen position with respect to the slide.

Advantageously means are arranged at the work-engaging faces of the fingers in such manner as to prevent accidental withdrawal of a work-piece held thereby. To this end the work-engaging face of each finger may be formed with a groove, and a spring-actuated work-gripping member may be positioned in the groove in such

manner that it normally projects outwardly to a slight extent beyond the work-engaging face and downwardly in the direction in which the work-piece enters, but arranged so that it is capable of being pressed into the groove.

Advantageously the fingers are mounted in a slot formed in the finger-supporting member so that the top surface of the finger is substantially flush with the top surface of the supporting member. The fingers best are provided with a clamp-engaging surface formed below the top surface thereof, and a clamp engaging with the clamp-engaging surface of the fingers is positioned in a clamp-receiving recess adjacent to the finger-receiving slot in the supporting structure, with the top surface of the clamp substantially flush with the top surface of the supporting member. Such work-transfer means, in which the top surfaces of the supporting member, the work-engaging fingers, and the clamps all are flush, can be arranged to slide directly under a blanking die in order to receive a blank work-piece.

The slide of an eyelet machine may itself be formed to serve as the supporting member for the fingers, clamps and other component parts of the new transfer means. Alternatively the supporting structure may be in the form of a generally ring-shaped block which may be fastened in an opening of suitable size provided in the slide.

The invention will be better understood from the following description considered in conjunction with the accompanying drawing, in which

Fig. 1 is a view of the blanking and first forming stages of an eyelet machine equipped with a slide having the new transfer means mounted therein for transferring a blank from the blanking stage to the first forming stage;

Fig. 2 is a view of the machine shown in Fig. 1 after the slide and transfer means have been moved into position for action on the blank by the first forming punch and die;

Fig. 3 is a plan of the slide shown in Figs. 1 and 2;

Fig. 4 is a plan on an enlarged scale of the blank-transfer block mounted in the slide shown in Fig. 3;

Fig. 5 is a section taken substantially along the line 5—5 of Fig. 4;

Fig. 6 is a fragmentary section taken substantially along the line 6—6 of Fig. 4;

Fig. 7 is a front elevation of a work-engaging finger fitted with a modified form of work-gripping member;

Fig. 8 is a side elevation, partly in section, of the finger shown in Fig. 7; and

Fig. 9 is a plan of the portion of a slide which itself serves as the supporting member for the new transfer means.

The eyelet machine shown in Fig. 1 comprises a base plate 10 on which is mounted a die block 11. First and second forming dies 12 and 13 are mounted in the die block 11 directly below corresponding first and second forming punches 14 and 15. Bottom pins 16 and 17, which may be moved downwardly against the force of springs, are provided for ejecting work from the dies 12 and 13, respectively.

Supported on the die block 11 is a slide 18. The slide is secured by bolts 19 at one end to a connecting plate 20 on which are mounted cam rollers 21 and 22. A cam 23 is secured to a cam shaft 24 which rotates in timed relation with the operating mechanism for the punches. As the cam shaft 24 rotates, the cam 23 acts on the

cam rollers 21 and 22 to impart reciprocating motion to the slide 18.

Mounted directly above the slide is a blanking die 25 through which a strip of metal 26 is fed. A blanking punch 27 is mounted directly over the blanking die 25 for stamping out blanks from the strip metal 26. A blank-transfer block 28 is mounted in the slide for transferring the blanks to the first forming die and punch 12 and 14, and transfer fingers 29 (Fig. 3) are provided for transferring work-pieces from one forming stage to the next.

When the blanking punch 27 is brought down, it stamps out a blank 30 and carries it through the blanking die 25 to the bottom of the blank-transfer block, which at this time is in position under the blanking die to receive the blank. As shown in Fig. 1, the blanking punch 27 has just been retracted from stamping out a blank 30, which is held by the transfer block. The slide 18 is about to be moved to the left to transfer the blank 30 into position for action by the forming die and punch 12 and 14. In the views shown in Figs. 2 and 3, the slide 18 has been moved its full travel to the left, and the blank 30 is held by the transfer block over the die 12. The forming punch 14 is beginning its downward stroke and is about to perform the first forming operation on the blank. As this forming operation proceeds, the slide 18 is retracted by the cam 23 to bring the transfer block 28 back into position to receive the next blank stamped out by the punch 27.

The blank transfer block 28 with which the slide 18 is provided is shown in greater detail in Figs. 4 to 6. The transfer block 28 comprises a generally ring-shaped supporting block 31 which has been cut away to leave a segmental aperture 32 permitting retraction of the transfer block while the forming punch is still at a point below the top surface of the slide. The block 31 is formed with substantially radial slots 33 in which rigid fingers 34 are mounted. Each of the fingers 34 is provided with a work-engaging face 35 which faces into the central opening of the ring-shaped supporting block and engages the blank 30. The fingers 34 may be moved radially in the slots 33 to adjust the position of the work-engaging faces 35 for engagement with different sizes of blanks.

The slots 33 are deep enough so that the top surfaces of the fingers 34 are substantially flush with the top surface of the block 31. The finger bodies in the slots 33 are not as deep as the supporting block 31 is thick, and accordingly the fingers are formed with a depending projection 36 to present work-engaging faces 35 of substantially the full thickness of the block 31. The inner surface of the block 31 may be formed with recesses 37 aligned with the slots 33 so that the fingers 34 with their dependent front portions 36 may be retracted to a point where their work-engaging faces are substantially flush with the inner cylindrical surface of the block 31.

One edge of each of the fingers 34 is cut at an angle to provide a clamp-engaging surface 38 below the top surface of the fingers. Clamps 39 mounted in recesses 40 are provided with projections 41 arranged to engage with the clamp-engaging surfaces 38 of the fingers. The clamps 39 are held in place by recessed-head screws 42 passing through the clamps and into engagement with the block 31. When the screws 42 are loosened, thus loosening the clamps 39, the fingers 34 may be moved radially with re-

spect to the block 31 to adjust the work-engaging fingers 35 to a position for accommodating a blank or other work-piece of given size. When the fingers 34 have been adjusted to the proper positions, the screws 42 may be tightened, thus tightening the clamp projections 41 against the corresponding clamp-engaging surfaces 38 of the fingers so as to hold the fingers rigidly in the chosen position.

The top surface of the clamp 39 and of the head of the screw 42 are substantially flush with the top surface of the block 31 and with the top surface of the finger 34. The entire transfer means thus is such that it may set flush with the top surface of the slide 18 and move easily into position directly under the blanking die 25.

The working face 55 of each finger is provided with a vertical groove 43. In the specific embodiment of the invention shown in Figs. 4 to 6, work-gripping means in the form of a leaf spring 44 is mounted in the groove 43 of each finger, and is so arranged that it normally projects outwardly slightly beyond the work-engaging face 35 and downwardly in the direction in which the blank enters. The arrangement of the spring is such that it may be depressed so that it lies wholly within the groove. A convenient way of mounting the springs 44 in the respective fingers is to form a recess 45 in the top surface of the finger, and to bend the spring over so that the bent-over portion lies in this recess. The spring may then be anchored in position by a pin 46 engaging the spring near the bend, and by a punch-prick 47 at the edge of the recess to anchor the rear end of the spring in the recess 45. The work-gripping springs 44, arranged as described, permit the work-piece 30 to be pressed easily into the transfer means by the blanking punch 24 but prevent it from being accidentally withdrawn on the upstroke of the punch, even though the lubricant with which the blank 30 and the punch 24 are coated tends to make the blank 30 adhere to the bottom of the punch.

As shown in Fig. 5, the springs 44 terminate at a point above the bottom of the finger work-engaging faces 35 corresponding to the thickness of the blank 30, so that upon retraction of the blanking punch from the transfer means, the springs press outwardly over the top surface of the blank 30. In this manner the blank 30 is positively engaged to prevent it from being drawn up or tilted as the punch is retracted or during movement of the slide. It has been found, however, that this particular arrangement of the springs is not essential. If desired, the springs may extend downwardly to the very bottom of the work-engaging faces 35, and when so arranged, the force with which they press on the edge of the blank is sufficient to prevent the blank from being accidentally withdrawn, either wholly or partially, on the upstroke of the punch.

The transfer block shown in Figs. 4 to 6 may be locked in position in a suitable opening in the slide 18 by a tightly fitting screw or pin 48 engaging in a recess 49 formed in the outer cylindrical surface of the blocks 31 and in a corresponding recess formed in the slide.

In Figs. 7 and 8 is shown a form of work-engaging finger which may be used in the transfer block in place of the specific form of fingers shown in Figs. 4 to 6. The finger 50 of Figs. 7 and 8, like the fingers 34 of Figs. 6 to 8, is

formed with a work-engaging face 51, and with a dependent front portion 52 so as to present a work-engaging face of substantially the full thickness of the block in which the finger is to be mounted. One edge of the finger 50 is cut at an angle to provide a clamp-engaging surface 53 below the top surface of the finger, so as to permit the finger to be held by a clamp in a supporting block with the top surface of the finger substantially flush with the top surface of the block.

A vertical slot 54 is formed in the work-engaging face 51 of the finger. A work-gripping member 55 is pivotally mounted in the slot 54 by a pin 56. A coil spring 57 is positioned in a hole drilled into the body of the finger 50 below the pivot pin 56, and this spring presses outwardly against the back of the work-gripping member 55. The coil spring 57 causes the work-gripping member 55 normally to pivot outwardly a slight distance beyond the work-engaging face 51 and project downwardly in the direction in which work enters a block in which the finger is mounted. Under pressure of a work-piece entering such block, however, the work-gripping member may be pressed into the slot 54, and in this position the work-gripping member 55 is urged by the compressed coil spring 57 into gripping engagement with the work-piece so as to prevent accidental withdrawal of the work-piece from the transfer block.

Advantageously the front face of the member 55 is cut at the bottom to form a notch 58 of about the same thickness as the work-piece which the transfer block is intended to receive. With the member 55 notched in this fashion, a work-piece inserted to the bottom of the transfer block is caught in the notch 58 and thereby is positively held against accidental withdrawal from the transfer block.

Work-engaging fingers constructed as shown in Figs. 7 and 8 have the advantage of making use of coil springs rather than leaf springs to actuate the work-gripping member, and in severe service coil springs are less subject to breakage than leaf springs.

The use of a completely removable transfer block of the character shown in Figs. 4 to 6 is advantageous, but, if desired, adjustable work-engaging fingers 60 may be mounted by clamps 61 directly in slots 62 formed in a slide 63, as shown in Fig. 9. The fingers 60 may be constructed either as shown in Figs. 4 to 6 or as shown in Figs. 7 and 8, and the clamps 61 may be made substantially the same as described above with reference to the transfer block of Figs. 4 to 6. In this embodiment of the invention the slide 63 itself, rather than a removable ring such as the ring 31, serves as the supporting member for the work-engaging fingers.

Work-transfer means constructed according to the invention does not suffer from the effects of wear, which necessitates frequent replacement of transfer means of the type heretofore most commonly employed. Whatever slight amount of wear might occur can readily be compensated for by appropriate adjustment of the work-engaging fingers. Moreover, the new transfer means can accommodate a wide variety of sizes and shapes of blanks or other work-pieces. In consequence of these advantages, the new transfer means are considerably more economical to use than transfer means of the character heretofore employed, even though the initial ex-

pense of making the new transfer means may be somewhat higher.

I claim:

1. In an eyelet machine or the like, a slide, and work-transfer means mounted on the slide comprising a plurality of work-engaging fingers, said fingers being slidably adjustable in the plane of the slide to accommodate work-pieces of different sizes and being wholly disposed between the top and bottom surfaces of the slide, and means for securing the fingers rigidly in a chosen position with respect to the slide, said securing means also being wholly disposed between the top and bottom surfaces of the slide.

2. In an eyelet machine or the like, a slide having on opening formed therein for the reception of a work-piece, a plurality of work-engaging fingers mounted about the periphery of said opening and slidably adjustable in the plane of the slide to accommodate work-pieces of different sizes inserted into said opening, said fingers being wholly disposed between the top and bottom surfaces of the slide and clamp means also disposed wholly between the top and bottom surfaces of the slide for securing the fingers rigidly in a chosen position with respect to the slide.

3. A work-engaging finger for apparatus of the character described comprising a finger body having a work-engaging face at one end thereof, and spring-actuated means arranged at said face normally projecting outwardly to a slight extent and downwardly in the direction in which a work-piece enters into engagement with the finger but being capable of being depressed to permit a work-piece to be introduced easily into engagement with the finger.

4. A work-engaging finger for apparatus of the character described comprising a finger body having a work-engaging face at one end thereof, said face being formed with a groove therein, a work-gripping member pivotally mounted in said groove, and a coil spring pressing against said work-gripping member in such manner that the member normally projects outwardly to a slight extent beyond the work-engaging face but may be pressed into the groove against the spring pressure.

5. A work-engaging finger for apparatus of the character described comprising a finger body having a work-engaging face at one end thereof, said face being formed with a groove therein, a work-gripping member pivotally mounted in said groove, a front face of said work-gripping member being notched adjacent the bottom thereof and a coil spring pressing against said work-gripping member in such manner that the member normally projects outwardly to a slight extent beyond the work-engaging face but may be pressed into the groove against the spring pressure.

6. A work-engaging finger for apparatus of the character described comprising a finger body having a work-engaging face at one end thereof, said face being formed with a groove therein, and a leaf spring positioned in said groove normally projecting outwardly to a slight extent beyond

the work-engaging face but capable of being depressed to assume a position wholly within the groove.

7. In apparatus of the character described, a finger-supporting member formed with a finger-receiving slot and an adjacent clamp-receiving recess, a work-engaging finger mounted in said slot with its top surface substantially flush with the top surface of the supporting member, a clamp-engaging surface formed on said finger below the top surface thereof, and a clamp positioned in said clamp-receiving recess in engagement with the clamp-engaging surface of the finger and with its top surface substantially flush with the top surface of the supporting member.

8. A transfer block for an eyelet machine or the like comprising a generally ring-shaped supporting block, a plurality of fingers having work-engaging faces extending into the central opening of said block mounted for adjustment by sliding in a radial direction on the block, and means for securing the fingers rigidly in a chosen position with respect to the block, said fingers and said securing means both being disposed wholly between the top and bottom surfaces of said block.

9. A transfer block for an eyelet machine or the like comprising a generally ring-shaped supporting block, a plurality of rigid fingers having work-engaging faces extending into the central opening of said block mounted for adjustment by sliding in a radial direction on the block, and a clamp associated with each of said fingers for securing each finger rigidly in a chosen position with respect to the block, said fingers and clamps both being disposed wholly between the top and bottom surfaces of said block.

10. A transfer block for an eyelet machine or the like comprising a generally ring-shaped supporting block, a plurality of fingers having work-engaging faces extending into the central opening of said block mounted for adjustment in a radial direction on the block, spring means mounted on said work-engaging faces in such manner as to prevent accidental withdrawal of a work-piece held thereby, and releasable clamp means for securing the fingers rigidly in a chosen position with respect to the block.

11. A transfer block for an eyelet machine or the like comprising a generally ring-shaped supporting block formed with a plurality of radially-extending finger-receiving slots and adjacent clamp-receiving recesses, fingers having work-engaging faces extending into the central opening of the block mounted in said slots and adjustable therein in a radial direction, the top surfaces of said fingers being substantially flush with the top surface of the supporting ring, a clamp-engaging surface formed on each of said fingers below the top surface thereof, and a clamp positioned in each of said clamp-receiving recesses in engagement with the clamp-engaging surfaces of the adjacent finger and with its top surface substantially flush with the top surface of the supporting ring.

ARTHUR L. WILLIAMS.
